UNITED STATES PATENT OFFICE.

MORRIS J. LIFSHITZ, OF NEW HAVEN, CONNECTICUT.

FIRE-ESCAPE.

932,793.

Specification of Letters Patent. Patented Aug. 31, 1909.

Application filed March 30, 1908. Serial No. 424,007.

To all whom it may concern:

Be it known that I, MORRIS J. LIFSHITZ, a citizen of the United States, residing at New Haven, in the county of New Haven and State of Connecticut, have invented certain new and useful Improvements in Fire-Escapes, of which the following is a specification, reference being had therein to the accompanying drawings.

10 My invention relates to new and useful improvements in fire escapes having for its object, among other things, to provide a device that will be a safe and effective means for escape from a building in case of fire, 15 that may be readily fixed in position for use, and when not in use may be folded into a neat and compact mass that will occupy the minimum space.

To these, and other ends, my invention 20 consists in the fire escape having certain details of construction and combinations of parts as will be hereinafter described and more particularly pointed out in the claims.

Referring to the drawings in which like 25 numerals of reference designate like parts in the several figures; Figure 1 is a front elevation of a building showing my improved fire escape attached thereto and ready for use; Fig. 2 is a view of the device when 30 folded and not in use; Fig. 3 is an enlarged section upon line A—B of Fig. 1 showing the window frame and the parts of my improved fire escape connected therewith; Fig. 35 4 is an enlarged fragmentary view of the bottom end of one of the chute sections; Fig. 5 is a perspective view of the frame; and Fig. 6 is an enlarged sectional plan view thereof upon line C—D of Fig. 5.

In the practice of my invention I provide- 40 a metal frame 1, shown in the drawings as being rectangular, but may be made of any other desired shape, having a lip 2 upon one side thereof, through which is slidable the tongue 4, and attached thereto are the grip- 45 ping arms 3—3. The chute is made of canvas, or other flexible material, in sections, the chute section 5 being secured at one end to the frame 1 and having the upper portion of asbestos or other non-inflammable mate- 50 rial, and to the lower end of which is se- cured, by rings or other fastening means, the chute section 6, to the lower end of which another section 6' is attached. The number 55 of these sections is limited only by the height of the building, enough being secured to- gether to reach from the window where the

device is attached to the ground. The lower ends of the chute sections are slotted at 7 so that they may be the more readily secured together, and adjacent thereto are the straps 8 60 having the rings 9—9 at their outer ends which are grasped by firemen or spectators to steady the device while persons are passing therethrough. Fixed to the inner end of the tongue 4 is a guide rope 10 which passes down through the inside of the chute and is 65 grasped by the person in the chute to limit the speed of his movement therethrough.

When not in use the device is compactly 70 folded, as shown in Fig. 2, and stored con- veniently adjacent to the window, and is applied by throwing the chute out of the window and adjusting the frame 1 so that the arms 3 rest upon the top and inner edges of the window frame with the inner end of 75 the tongue 4 also abutting against said frame, as shown in Fig. 3. The person then steps into the chute section 5 through the frame 1, grasping the rope 10 and passes down through the chute, governing his 80 speed by said rope. It is presumed that at a fire where this device is used there will be some persons around the building, either 85 firemen or spectators, who will grasp the rings 9 of the lower chute section and steady 90 the device so that several persons in rapid succession might slide therethrough and their movements after they are first dis- charged from the chute controlled by those persons in the vicinity.

The chute section 5, being adjacent to the wall of the building, is provided with a portion (shaded in Fig. 1) of indestructible material.

The device is removed from the building 95 from the outside by pulling upon the ropes 11 which slide through the rings 12 upon the underside of the several chutes, through the holes 13 in the lip 2, then through the hole 14 in the tongue 4, terminating and 100 fastened to the frame 1 through the hole 15. It is apparent that by pulling on the ropes 11 the frame 1 is drawn along the tongue 4 away from the window frame, and after the arms 3 are released from said window frame 105 the weight of the chute sections will pull the frame from the window sill and the same will drop to the ground by gravity.

There are minor changes and alterations 110 that can be made within my invention, aside from those herein shown and suggested, and I would therefore have it understood that I

do not limit myself to the exact construction herein shown and described, but claim all that falls fairly within the spirit and scope of my invention.

5. What I claim as new and desire to secure by Letters Patent, is—

1. In a fire escape, the combination with a frame; of arms connected therewith for separably securing said frame to the frame 10 of a window; a tongue slidably mounted within said frame and arranged to abut against the sill of said window frame; a flexible chute connected with said frame; a rope connected with said tongue and passing 15 through said chute; and means for moving said frame on said tongue and away from said window frame, comprising a second rope passing through said tongue and having one end thereof connected with said 20 frame.

2. In a fire escape, the combination with

a frame 1 having arms 3 connected therewith for separably securing said frame to the frame of a window; of a tongue 4 slideable therein and arranged to abut against the sill of said window frame; a flexible section 5 connected with said frame; a guide rope 10 passing through said chute and having connection with said frame; and a rope 11 passing through said tongue 4 and connected with said frame 1 in such a manner that by pulling on said rope the said frame will be moved on said tongue away from its engagement with said window frame substantially as described. 25 30 35

In testimony whereof I affix my signature in presence of two witnesses.

MORRIS J. LIFSHITZ.
